ARTHUR DORSEY, OF BROOKLYN, NEW YORK.

SWITCH MECHANISM.

Application filed October 24, 1923. Serial No. 670,408.

This invention relates to switch mechanism of the type which is to be thrown on and off automatically at predetermined times, and is designed primarily with reference to a so-called time switch in which a clock movement provides the motive power for actuating the switch for the desired control of a circuit, at stated times determined by a manual setting.

The invention has for its principal object to provide in a switch mechanism of the character described simple and positive actuating devices for invariably throwing a mechanical switch. More particularly, the invention seeks to provide on and off levers both movable in the same direction and disposed at the same side of the axis of turning of the switch element and both operable and under the influence of arms movable unidirectionally.

A further object of the invention is to provide switch mechanism in which all of the parts are mounted on a single shaft and movable about the same center. To this end, the invention in its preferred form contemplates the use of a rotating switch element.

Still another object of the invention is to actuate the switch member with what may be termed a double hammer blow, the operating element for the switch receiving in both the "on" and "off" movements its initial impulse from a coiled spring and being later assisted in its movement home by a supplemental spring designed to operate after the switch member has passed its dead center and termed hereinafter for convenience, a "toggle" spring.

Still another object of the invention is to associate with the "on" and "off" levers co-operating stops for limiting their travel and for resetting certain pawls associated therewith and arranged to pick up the switch member at the times intended, respectively, for effecting the desired movement thereof.

Still another object is to provide in switch mechanism a design for automatic actuation, a hand lever whereby the switch may be thrown on or off without disturbing the sequence of automatic operations for which the automatic actuator is set. In the improved switch the elements are so related as to permit simultaneous operation thereof by hand without permitting the switch to

stay on dead center and without jamming any of the parts.

Further objects of the invention have to do with matters of importance concerning the manufacture and assembling of the parts and the electrical connections therefor, the mechanical elements being mounted on an improved base which may have formed therewith a compartment for the terminals, thereby making a separate junction box unnecessary.

Reference is now to be had to the accompanying drawings for a detail description of the preferred embodiment, in which:

Figure 1 is a view in front elevation showing the parts assembled within the improved box, the lower portion of the front wall being broken away to show the junction box incorporated in the lower part thereof.

Figure 2 is a view in transverse section taken through the box shown in Figure 1 and indicating the relation and disposition of the several units of the switch mechanism.

Figure 3 is a view similar generally to Figure 1 but with the front plate removed.

Figures 4-9 and 11 show in elevation various parts of the switch mechanism in different positions and are intended to make clear the method of throwing the switch on and off automatically.

Figure 10 is a view in elevation of the parts shown in Figure 7 with the switch blades and bridge omitted in the interest of clearness and the pawl out of engagement with the yoke.

As indicated hereinbefore, the improved switch mechanism is designed primarily with reference to its use in association with a clock which may carry operating arms adapted to throw the switch on or off at predetermined hours depending upon the manual setting. The invention is not to be limited to such application and the drawings do not illustrate any of the details of the source of power for tripping the switch automatically. In the preferred construction a casing *a* having certain improvements therein is provided to receive the switch mechanism indicated in Figure 3. This casing *a* is adapted to receive a box *b* having a transverse wall *b'* therein to form with the bottom of the casing *a* a lower compartment

*b*² in which may be housed the terminals *b*³ and into which may be led through the bottom wall of the casing *a* the several wires *b*⁴ for connection with the respective terminals. Between the plate *b*' and the top wall *b*⁶ of the box *b* may be formed a separate compartment in which is housed the switch mechanism proper. The box *b* may be secured in the casing *a* by means of a single bolt *c* extending through the box and taking into the rear wall of the case the head *c*' of the bolt being exposed at the front of the box to facilitate removal of the self-contained unit comprised by the box *b* and the parts carried therein. A suitable door *a*' may be carried by the case to close it. The front wall *b*⁸ of the box *b* may have a sight opening *b*⁹ therein through which the hand operated lever *d* for the switch may be observed to ascertain, from the appropriate markings thereon whether the switch is off or on. The hand lever may extend upwardly through a slot *b*⁸ in the top wall of the box *b* for engagement with the finger to permit it to be thrown in one direction or another for actuation of the switch. It is obvious that the general characteristics of the improved mounting and the relationship and operation of parts, will not be altered by omitting the top compartment, as such, in switches designed for lower voltages.

Before describing the details of the switch mechanism it may be noted that generally speaking, automatic actuation thereof is effected through two levers one of which *e* may be termed for convenience the "off" lever and the other of which *f* may be termed the "on" lever since these levers when engaged by the power means are thrown to bring about such a condition of the switch. These levers *e*, *f*, may extend upwardly through slots *b*⁹, *b*¹⁰, respectively, in the top wall of the box *b* and be engageable periodically by power operated operating arms carried, for instance, by a clock mechanism which may be housed in the upper part of the casing *a*. One such operating arm *g*¹⁰ is indicated for clearness in Figure 1 and is shown in position about to pick up the lever *e* and move it towards the right for tripping. A similar arm will move for co-operation with the on lever *f*. The invention is not to be limited to the particular type of actuating mechanism employed except that one phase of the invention is concerned with the provision of on and off levers movable in the same direction and disposed on the same side of the axis of throw by arms which travel unidirectionally.

60 The switch illustrated herein is of the double pole type including two similar blades *g*, *g*', spaced apart but positively interconnected by a bridge *g*², and adapted to oscillate on a supporting shaft *h* fixed in three vertical brackets *i*, *i*', *i*², carried on a

common base *i*³, secured to the compartment plate *b*'. The invention is not limited to the precise character of the switch. In accordance with the invention it is proposed, however, to have all of the elements movable about the same center and this is accomplished by having all of the elements move about the supporting shaft *h*. Reference is now to be had to Figure 2 for an understanding of the elements which are carried by the shaft *h*. Commencing with the hand lever *d* which acts as a clamping washer there is seen a strip of insulation *k*, between the lever and the switch blade *g* and on the rear side of the switch blade a second strip of insulation *k*' which is clamped between the switch and a plate *g*³ which may be formed as a flange of the so-called bridge *g*² for positively interconnecting the switch blades *g*, *g*'. Suitable rivets *l* may pass through the hand lever *d* and the various elements just described and into the flange *g*³ thereby uniting all of the parts positively for simultaneous oscillation on the shaft *h*. The rivets *l* will, of course, be insulated from the switch blade *g*. In the same figure, at the rear end of the shaft *h* there will be found corresponding elements including a back clamping washer *l*', insulation pieces *k*², *k*³, at opposite sides of the switch blade *g*' and a clamping plate *g*⁴ which may be formed as a flange on the rear end of the so-called bridge *g*². The last named parts *l*', *k*², *g*', *k*³, and *g*⁴, are united so as to move as a unitary structure with the elements connected with the other blade *g* as heretofore described. Hand operation of the switch members by oscillating the lever *d* will now be clear. Automatic operation through the on and off levers *e*, *f* is to be described. While reference has been made hereinbefore to a single shaft *h* this shaft, in fact, is made in two aligned sections in order that a space may be afforded for what may be termed a toggle spring *m* which is adapted to act on the switch mechanism after it passes dead center to assist in throwing it home, and then holding it yieldingly in the on or off position. As shown, one end of this toggle spring *m* is anchored on a pin *u* carried with the bracket *i*' and the other end is anchored at the other side of the axis of the shaft *h* on an arm *h*' journaled on the rear shaft section *h*². This rear shaft section *h*² rocks with the switch blade *g*' and the associated parts so that all such parts are subject to the tension of the spring *m* when the switch is thrown on or off, as will later appear. The front shaft section *h*, on the other hand, may be held against rotation while the front switch member *g* and the associated parts oscillate thereon.

Again referring to Figure 2 the bracket *i* carries an ordinary coiled spring *n* one end of which is fixed and the other end of

- which is connected operatively with the "off lever *e*" which oscillates about the shaft *h*, the action of the spring being to throw the lever *e* in a counterclockwise direction.
- 5 The bracket *i'* has anchored to its front face an ordinary coiled spring *o* the other end of which is engaged operatively with the throw member *f'* of the on lever *f* the action of the spring *o* being to tend to revolve the throw member *f'* in a counterclockwise direction. One arm *f²* of the throw lever *f'* is slotted as at *f³* to receive a pin *f⁴* carried on the tail of the on lever *f* which is pivoted on the bracket *i'* as at *i⁵*.
- 10 Accordingly, oscillation of the on lever *f* in one direction will bring about oscillation of the throw lever *f'* in a contrary direction.
- 15 The arm *h'* which is subject to the action of the toggle spring *m* is formed with a yoke *h³* the other end of which is journaled on the front shaft section *h* as indicated by the bearing ring *h⁴*. This last named end of the yoke also carries an upwardly extending arm *h⁵* provided with a flange *h⁶*
- 20 for engagement by a pawl *e'* pivoted as at *e²* on the off arm *e*. The tail *e³* of the pawl is adapted to engage a stop *i⁶* carried with the bracket *i* when the off lever *e* is carried by the power actuator to its extreme right hand position as indicated in Figure 8. When the tail *e³* of the pawl engages the stop *i⁶* the pawl will be rocked about its pivot *e²* and its end thrown into the path of the flange *h⁶* so that upon release of the arm *h'* when it is moved to the left under the influence of the coil spring *n* and, later, the toggle spring *m*, the yoke *h³* will be rocked about the shaft *h* in a counterclockwise direction. The arm *h'* which is integral with the yoke *h³* is also integral with an arm *h⁵* which moves with the yoke in the manner described and, when the switch members are engaged with the terminals *g⁵* engages the bridge *g²* which positively connects the switch members and throws the switch member in a counterclockwise direction into the "off position" illustrated in Figure 3. Figure 11 illustrates the relation of the arm *h⁵* to the bridge *g²* at the end of this off movement while Figure 5 indicates the relation of the arm *h⁵* to the bridge *g²* before the off lever is tripped. After the off lever is tripped to throw the switch into the off position the tail *e³* of the pawl will engage a pin *i⁷* on the bracket *i* and limit the movement of the off lever *e*, and throw the pawl out of the path of the flange *h⁶*.
- 25 Reference is now to be had to Figures 6 and 7. In these figures it appears that the throw lever *f'* whereby the switch is to be moved on to position, has a downwardly extending arm *f⁶* on which is pivoted as at *o⁸* a pawl *o'*. The tail *o²* of this pawl engages a fixed abutment *i⁸* on the bracket *i'* when the throw lever *f'* is oscillated to its
- 30 extreme position in a counterclockwise direction under the influence of the on lever *f* when the latter is moved to the right in a clockwise direction as shown in Figure 6. Engagement of the tail *o²* of the pawl *o'* with the stop *i⁸* serves to rock the pawl and throw its nose into operative relation with the yoke *h³* so that when the arm lever *f* is tripped and rotated in a counterclockwise direction under the influence of the springs *o* and *m*, and the throw lever *f'* is simultaneously oscillated in a clockwise direction the pawl will oscillate the yoke *h³* in a clockwise direction to throw the switch members on. This is done by engagement of the yoke *h³* with the underside of the bridge *g²* as shown in Figure 7. In this figure the switch member *g¹* is fully home and the yoke *h³* has been carried beyond the pawl *o'* movement of the throw lever *f'* having been arrested by engagement of the tail of the pawl with a pin *i⁹* on the bracket *i'*.
- 35 The relation of the position of the parts will now be considered briefly with reference to Figures 4-11. As shown in full lines in Figure 5 the switch members are on. At this time, the toggle spring *m* is effective to exert its pressure to revolve the switch members on the shaft *h* in a clockwise direction thereby maintaining the blades in engagement with the terminals *g³*. When the off lever *e* is picked up by the power operating arm and moved to the position shown in Figure 8 the pawl *e'* is brought automatically into line with the flange *h⁶* on the arm *h⁵* 100 of the yoke *h³* so that when the arm *e* is released the springs throw it to the left, the first action being for the pawl *e'* to forcibly engage the flange *h⁶* in its movement to the left and the next action for the arm *h⁵* to forcibly engage the upper side of the bridge *g²* and rock the switch members out of engagement with the terminals *g³*. The movement may be said to include a double hammer blow and the toggle spring at all times 105 is effective to assist in carrying the switch home as it passes dead center. When the appropriate power arm picks up the on lever *f* and moves it to the position shown in Figure 6 at which time it is about to be tripped the pawl *o'* will be rocked about its pivot *o* through engagement of the tail *o²* with the abutment *i⁸* so that upon release of the on lever *f* the pawl will pick up the yoke *h³* forcibly and the yoke *h³* will move in a clockwise direction until it forcibly engages the rear side of the bridge *g²* thereby oscillating the switch members into engagement with the terminals. The toggle spring *m* passes through the center of the shaft *h²* and assists in carrying the switch elements home.
- 40 An important feature of the construction adapting the mechanism to winter use in exposed locations resides in the provision of a heating coil indicated schematically at *r* in

Figures 1-3. This heating coil is located in an acceptable position on the insulating top plate of the compartment for the switch mechanism proper and at a point immediately below the clock. For convenience in mounting and demounting the coil for use according to winter requirements it has downwardly depending terminals r' , r^2 , which when projected through slots in the top plate of the compartment come into contact yieldingly with the terminals g^3 thereby automatically completing the circuit through the coil of the heating unit. The coil which may be of any suitable form is mounted within convenient reach and is adapted for ready removability.

Changes in matters of design and arrangement of parts may be made without departing from the spirit of the invention.

20 What I claim is:—

1. Switch mechanism comprising a switch element, pivoted operating levers therefor movable in the same direction, and means interposed operatively between the respective levers and the said switch for moving the same into off and on position as desired upon movement of the appropriate lever in the said direction.

2. Switch mechanism including a switch element, means to mount the element for rotation, pivoted operating levers therefor disposed at one side of said axis and movable in the same direction, and means operatively interposed between the respective levers and the switch element to oscillate the switch element into on or off position upon swinging movement of the appropriate lever.

3. Switch mechanism comprising a switch element, pivoted operating levers therefor movable in the same direction, and means interposed operatively between the respective levers and the said switch for moving the same into off and on position as desired upon movement of the appropriate lever in the said direction, and power means rotatable uni-directionally for operating the respective levers periodically.

4. Switch mechanism including a switch element mounted for rotation, pivoted operating levers therefor disposed at one side of the axis of said element, means interposed operatively between one of said levers and the switch element at a point above said axis to move the switch element in one direction, and means interposed between another of said levers and the switch element below said axis to move the switch element in a counter-direction.

5. In switch mechanism an insulated mounting for the mechanism having a transverse horizontal partition of insulating material forming a base to support said mechanism, said mounting forming a partial closure for said mechanism, terminals carried by said partition and separated thereby from

the said switch mechanism, a front insulated plate secured to the mounting and forming a complete closure for the mechanism and a casing to receive said mounting, having a detachable front wall.

6. In switch mechanism, a mounting for the said mechanism formed of insulating material and providing a partial closure therefor, manually operating means for the mechanism, means to pivotally mount the means within the casing to provide an externally projecting portion, means on the pivotally mounted member to indicate the condition of the mechanism, a front insulated plate forming a complete closure therefor and a sight opening therein to expose the indicating means.

7. A mechanical switch mechanism including switch blades mounted to oscillate on a fixed axis, means to oscillate the said blades, said means being mounted for operation about the same fixed axis, and means movable uni-directionally for initiating operation of said operating means.

8. Switch mechanism including switch blades mounted to oscillate on a fixed axis, operating levers therefor mounted to swing on the same axis, means operatively interposed between said levers and said blades adapted to swing on the same axis for transmitting movement of the levers to the said blades and power means operative to accelerate movement of said operating levers.

9. Switch mechanism including switch blades, a shaft on which the blades are mounted for oscillation, operating levers mounted to swing on the same shaft, means interposed operatively between the respective levers and the blades to transmit movement of the levers to the blades, said means being mounted for movement on the same shaft and power means operative to accelerate movement of said operating levers.

10. In combination with switch mechanism comprising a switch element adapted to oscillate on a fixed axis, operating levers mounted to move in the same direction, power means for moving the said operating levers, springs operatively engaged with the respective levers to oppose such movement yieldingly, and means interposed operatively between the respective levers and the switch element to transmit movement of the levers to the switch element.

11. In switch mechanism in combination with a switch element adapted to oscillate on a fixed axis, operating levers therefor movable in the same direction, and means independent of the switch element and the levers but engageable by the respective levers upon movement thereof for transmission of the movement of such levers to the switch element.

12. Switch mechanism including a switch element adapted to oscillate on a fixed axis,

- pivoted operating levers therefor adapted to be oscillated on their respective pivots for operation of the switch element, said levers being movable freely in one direction independent of the switch element, and means carried with the said levers to engage the switch element when the said levers move in a counter-direction for actuation of the switch.
- 10 13. Switch mechanism including a support, means to mount the mechanism on a fixed axis on the support, a switch element adapted to oscillate on the fixed axis, an operating member for the switch element adapted to oscillate on the same axis, and a spring connected to the support and engaged restrainingly with the said operating member to resist movement thereof in both directions of oscillation.
14. In switch mechanism a mounting for 20 the mechanism having a transverse horizontal wall of insulating material below which the mechanism is supported, said wall having slots therein, switch terminals mounted below the wall, and a heating unit adapted 25 to be mounted on the wall and provided with terminals to extend through the slots and engage the respective terminals.
- This specification signed this 29th day of September A. D. 1923. 30

ARTHUR DORSEY.
